UNITED STATES PATENT OFFICE.

GEORGE H. HILL, OF SCHENECTADY, NEW YORK, ASSIGNOR TO GENERAL ELECTRIC COMPANY, A CORPORATION OF NEW YORK.

SYSTEM OF MOTOR CONTROL.

No. 836,973.

Specification of Letters Patent.

Patented Nov. 27, 1906.

Application filed May 20, 1905. Serial No. 261,293.

To all whom it may concern:

Be it known that I, GEORGE H. HILL, a citizen of the United States, residing at Schenectady, county of Schenectady, and State of New York, have invented certain new and useful Improvements in Systems of Motor Control, of which the following is a specification.

The present invention relates to systems of motor control, and more particularly to electrically-operated pneumatically-controlled systems for governing the operation of the motors of a car or train.

More specifically the present invention relates to the system of control disclosed in Patent No. 809,908, granted on January 9, 1906, on an application filed by F. E. Case, and has for its object to improve certain features of that system.

In the aforesaid application a motor-controller of the automatic electromagnetically-actuated type is governed in its operation by means of a pneumatic system comprising a master-valve and but two train-pipes acting through a number of relays. The relays serve to complete the control-circuits for the motor-controller and are arranged to operate under different pressures, the master-valve being adapted to supply the two pipes successively with air having the proper degree of compression. Both pipes are energized during each cycle of operation, the direction of rotation of the motors being determined by the order in which the pipes are energized.

In one of its aspects the present invention consists in an automatic motor-controller and a pneumatic governing system therefor comprising two pipes and a series of independent relays associated therewith, the relays being grouped in pairs, so that half are controlled by one pipe and half by the other, producing a simple and symmetrical construction and arrangement of parts having an efficient and certain action.

In another of its aspects the present invention consists in an automatic motor-controller having a reversing-switch and a pneumatic governing system comprising two pipes and a series of relays including a reversing-relay connected to each pipe, the relays being adapted to operate under different pressures, together with a valve for supplying compressed air to the pipes, the arrangement being such that both pipes must be en-

ergized to produce a complete cycle of connections for forward or reverse rotation of the motors, the direction of rotation of the motors being determined by the order in which the pipes are energized, and the last pipe to be energized being supplied with air only at a pressure sufficient to operate the reversing-relay associated therewith, whereby the admission of air to the second pipe cannot alter the direction of rotation of the motors as determined by the pipe which is first energized.

In another of its aspects the present invention consists in a motor-controller, a governing-relay, the operation of which causes the controller to connect the motor or motors for forward rotation, a second relay, the operation of which causes the controller to connect the motor or motors for reverse rotation, together with means associated with each relay for rendering the other relay inoperative, whereby neither relay is capable of producing an operation of the controller until the other relay is in its inoperative position.

The present invention in these and other of its aspects will be more fully understood, and further objects will be apparent in connection with the following description thereof.

A preferred form of the present invention is illustrated in the accompanying drawings, in which—

Figure 1 illustrates one system of motor-circuits, motor-control apparatus, and pneumatic governing means arranged in accordance with the present invention. Fig. 2 is a view, partly in section, showing the construction of the relays and the arrangement thereof. Fig. 3 is a bottom plan view of the parts shown in Fig. 2. Fig. 4 is a cross-section of a suitable form of master-valve. Figs. 5, 6, and 7 are views showing the relation of the main valve and valve-seat during the several operative positions of the valve. Fig. 8 shows a train of two cars equipped in accordance with the present invention.

Similar reference characters will be used throughout the specification and drawings to indicate like parts.

The particular form of apparatus illustrated consists of a two-motor-car equipment arranged to be controlled from either end of the car.

M' and M^2 are the two motors.

C is a motor-controller, including a series

of individual contacts T , T' , T'' , and T''' for connecting the motor-circuit to the source of current-supply, indicated by a collecting-shoe or trolley T ; S , for connecting the motors in series; P and P' , for producing the parallel connections of the motors; R' to R'' , for governing the resistance-sections R^a to R^e , and B , for connecting a shunt about the resistance and series switches, whereby the motor-circuits are prevented from being broken during the change from series to parallel.

CB is a circuit-breaker located in the main circuit, and RS is a reversing-switch, which determines the direction in which current flows through the motor-armatures.

The circuit-breaker, the motor-controller, and the reversing-switch are governed by a pneumatic system, comprising a pair of train-pipes 1 and 2, which may be connected to atmosphere or to a compressed-air reservoir A by means of either of the master controlling-valves V and V' . Connected to the two pipes is the circuit-breaker-actuating mechanism D, which comprises a double-piston mechanism, such as is disclosed in application of F. B. Corey, filed October 1, 1904, Serial No. 226,754. A series of cylinders containing pistons E, F, and G is connected to pipe 1, and a similar series containing pistons E', F', and G' is connected to pipe 2. The pistons E, E', F, F', G, and G' serve to control the several relays to be hereinafter described. The pistons are of varying diameters—namely, the pistons E and E' have the largest diameters, F and F' somewhat smaller diameters, and G and G' the smallest diameters. Above each of the pistons is a spring 24, which normally holds the piston in its lower position. By making the several springs uniform the pistons of each set will operate under different pressures.

In actual practice the circuit-breaker-actuating device D and the pistons E and E' are arranged to operate at about seven and a half pounds pressure, the pistons F and F' at twenty-five pounds pressure, and the pistons G and G' at forty pounds pressure. The relays operated by the pistons E, E', F, F', and G, G' control the actuating and maintaining circuits for the motor-controller and reversing-switch by alternately connecting these circuits to and disconnecting them from trolley. The control-circuits terminate in five wires 4, 5, 6, 7, and 8, which are adapted to be connected to wire 3, connected to the current-collector through the manually-operated switch X.

Assuming that air at twenty-five pounds pressure is admitted to pipe 1, it will be seen that the circuit-breaker CB will be closed and pistons E and F will be operated. The operation of piston E and the closing of the relay e controlled thereby produces no effect upon the controller, since both relay e and relay e' must be closed in order to connect wire 8 to

trolley. The operation of piston F and the consequent closing of relay f permits current to flow from wire 3, through relay f , through interlock f^1 , which is connected with piston F' and normally closed, and thence through wire 4 and through the actuating-coil r of the reversing-switch, causing the reversing-switch to be thrown to the position shown. The line-contacts T , T' , T'' , and T''' are operated by current flowing through wire 4, which current after the reversing-switch has been operated passes through contacts w w' on the reversing-switch, through the actuating-coils of the line-contacts, to ground. Another circuit is established from wire 3 through relay f^2 , associated with piston F, and thence through wire 6, through contacts p^2 of parallel switch P, through the actuating-coil of the series contact S, interlock b^3 , associated with the bridging-contact B, thence through the lowermost contacts of interlocks i' , i^3 , i^5 , and i^7 , associated with the resistance-contacts R^4 to R^e , inclusive, to ground, closing the series contact. The operation of the circuit-breaker, piston E, and piston F consequently serve to complete a circuit through the motor in series with each other and, as may be seen by tracing the circuit shown on heavy lines, in series with the entire resistance. If now pressure is raised in pipe 1 to forty pounds, operating piston G, relay g is closed and current is free to flow from wire 3, through relay g , wire 7, to upper set of the auxiliary contacts s , associated with series switch S, wire 9, coil o of the combined throttle and time-interval relay O, contact o' of this relay, thence through the lower contacts of interlock i , associated with switch R^4 , through the actuating-coil of the switch R^4 , thence through the lower contacts of interlocks i^3 , i^5 , and i^7 , to ground. Switch R^4 is closed, cutting out resistance-section R^d . The closing of switch R^4 interrupts the actuating-circuit and causes a maintaining-circuit to be established in that the actuating-circuit of switch S is shifted from the lowermost contacts of the interlock i' to the upper contacts of this interlock, and thence through the actuating-coil of switch R^4 and to the ground, as before. The actuating-circuit of switch R^4 is transferred from lower contacts of the interlock i to the upper contacts of this interlock, and thence to the lower contacts of interlock i^2 , associated with switch R^3 , through the actuating-coils of switches R^3 and R^5 , through the lowermost contacts of interlocks i^5 and i^7 to ground. Contacts R^3 and R^5 are thereupon closed and resistance-sections R^e and R^d are removed from the motor-circuit. Similarly the remaining resistance-sections are eliminated automatically and progressively, until finally switch B is closed, serving to place a shunt about the resistance and series switches and cause said switches to open. Pressure in pipe 1 may now be reduced to twenty-five

pounds, leaving the motors connected across the line in series with each other and with no resistance in circuit. If now pipe 2 is energized with air at seven and a half pounds pressure, piston E' will be operated, closing relay e' , and since e has been previously closed current is free to flow from wire 3, through relays e e' , wire 8, the lower contacts of interlock s of series switch S, through the actuating-coils of parallel contacts P and P', through the upper of the contacts of interlock b^3 , associated with contact B, through wire 10, and through the lower contacts of interlocks i^1 i^3 i^5 i^7 , to ground. The closing of the parallel switches 5 interrupts the maintaining-circuit for the bridging-contact B at the lowermost contact of interlock p^2 , associated with parallel contact P, and the bridging-contact is allowed to open. In opening, the bridging-contact 10 breaks the actuating-circuit of the parallel contacts, but a maintaining-circuit for these latter contacts has previously been established at interlock p' , associated with parallel contact P'. The motors are now connected 15 in parallel with all the resistance in circuit. Pressure in pipe 1 may again be raised to forty pounds, operating piston G and closing relay g , whereupon the resistance will again be automatically and progressively cut out. 20

If it is desired to operate the motor in the reverse direction, pipe 2 is energized first, closing the circuit-breaker, relay r' , and operating the piston F'. The operation of piston F' closes relay f^0 and allows current to flow from wire 3 through this relay, interlock f' , associated with piston F, wire 5, to actuating-coil r' of the reversing-switch and after the reversing-switch has operated through the actuating-coils of the line-contacts, as before. 25 The piston F' also closes relay f^{20} , which completes the connection of wire 6 to wire 3 and permits the series-contact to be closed. Upon raising the pressure in pipe 2 to forty pounds the resistance is automatically cut out, and upon reducing the pressure in this pipe to twenty-five pounds and energizing pipe 1 with air at seven and a half pounds pressure the actuating-circuit for the parallel contacts is completed, and the motors are connected in parallel with all resistance in circuit. Upon again raising the pressure in pipe 2 to forty pounds the resistance is cut out, as before. 30

It is noted that current cannot be supplied to either operating-magnet for the reversing-switch until the controlling-piston for the other electromagnet is in its retracted position, and, furthermore, after the reversing-switch has once been thrown it is unaffected by admission of air to the second pipe, since the air in the second pipe is at so low a pressure that any possibility of operating the controlling-piston for the reversing-relay connected with the second pipe is eliminated. 35

The use of this low pressure in the two pipes is made possible by reason of the two relays in the controlling-circuit for the parallel switches, each relay being controlled by one of the pipes and it being necessary that both be closed before the parallel switches can be operated for either direction of rotation of the motors. 40

The master-valve for controlling the admission of air to the pipes and for exhausting them is shown as consisting of a plug-valve v and disk valve v' . The plug-valve serves to connect either of the pipes 1 and 2 with either port 11 or port 12 in the main valve-casing. In the position shown pipe 1 is connected to port 12 and the motors may be connected 45 for rotation in one direction; but if the plug-valve v is operated to connect pipe 1 to port 11 the motors will operate in the opposite direction. When the valves v and v' are in their normal inoperative positions, 50 they are exhausted by being connected to atmosphere through ports 11 and 12 and ports 13 and 14 with valve v' . Upon moving valve v' in a clockwise direction until port 15 registers with port 12 air will flow from the 55 reservoir A, through pipe 16 and ports 15 and 12, and thence to whichever pipe is connected to the port 12. Port 15 is provided with a reducing-valve which admits pressure to the train-pipe at twenty-five pounds. In the 60 next position of the valve port 17 admits pressure to train-pipe at forty pounds, and in the third operative position port 18 causes the train-pipe, which is connected to pipe 12, to be exhausted until the pressure therein is 65 reduced to twenty-five pounds. At the same time, however, port 19 registers with port 11, and port 13 is closed, so that air is free to pass from the reservoir through port 11 to the second train-pipe, the pressure being limited, 70 however, by the reducing-valve in port 19 to seven and a half pounds. In the final position of the valve port 20 registers with port 12 and permits air to flow into the first pipe 75 at a pressure of forty pounds, completing the cycle of operations. 80

In Figs. 2 and 3 I have shown the controlling-relays arranged in a preferred manner. The cylinders within which the controlling-pistons are mounted are supported at the 85 base of the frame 21, and stems 22 project upwardly from the several pistons through a perforated flange 23. The springs 24 are arranged between the lower side of the flange 23 and the tops of the several pistons. 90 The movable contact members of the relays and interlocks are flexibly supported upon the stems 22 in order that they may properly position themselves in engaging with their co-operating fixed contacts. Magnetic blow-outs 95 are arranged adjacent each set of contacts except the contacts f' and f^{10} , which latter contacts do not operate to interrupt a circuit when current is flowing. The connections of the energizing-coils of the blow-out 100

magnets are indicated in the diagram of Fig. 1.

In Fig. 4 is illustrated in cross-section a suitable form of master controlling-valve for admitting air to either pipe at twenty-five and forty pounds pressure, to the other pipe at seven and a half pounds pressure, and for exhausting both pipes. This valve consists of a main slide-valve 26 and auxiliary slide-valves 27 and 28, the latter slide-valves controlling, respectively, ports 11^a and 12^a, corresponding to the ports 11 and 12 in Fig. 1. The valve 27 is controlled by the connected pistons 29 and 30, while the valve 28 is controlled by the connected pistons 31 and 32. The main valve 26 is moved by means of the operating-handle *h*. In the position of the parts shown the main valve is in its inoperative position, and ports 11^a and 12^a are connected to atmosphere through ports 33 and 34, respectively. Also the chambers 35 and 36 between the outer ends of the pistons 30 and 32, respectively, and the valve-casing are connected to atmosphere, the one through passage 37, port 38 in the valve 26, and ports 39^a and 39, and the other through passage 40, port 41 in the valve 26, and ports 39^b and 39. The chamber 35 is at all times connected to port 11^a by means of the passage 42, and the chamber 36 is at all times connected to port 12^a by means of the passage 43, so that the pressure behind the pistons is normally the pressure within the two pipes. A passage 44 extends from the valve-seat 45 to a point between the two pistons 29 and 30. Air is admitted to the chamber containing the valve 26 at forty pounds pressure by means of a pipe connected to the casing at 46 and then under the control of said valve to the pipes 1 and 2 in the sequence and at the pressures previously described.

The operation of the valve will be clear from an inspection of Figs. 5, 6, and 7 in connection with Fig. 4. Air is admitted to the ports 11^a and 12^a through ports 47 and 48, respectively. Normally these ports are closed by the main valve, as shown in Fig. 5, and at the same time the passages 37, 44 are connected to atmosphere through ports 39^a and 39 by means of the port 38 in the main valve, and the port 40 is connected to atmosphere by means of the ports 41 and the ports 39^b and 39. In Fig. 6, 26^a represents the main valve occupying its first running position—namely, passage 37 has been disconnected from atmosphere and port 47 has been uncovered by means of port 49 in the main valve. The space between the pistons 29 and 30 still remains connected to atmosphere, but the inner side of piston 29 is subjected to pressure of forty pounds through port 47, while the outer side of piston 30 is subjected to the pressure in port 11^a—namely, atmospheric pressure. As the air flows through port 47 the pistons 29 and 30 are

moved laterally to the left until the valve 27 shuts off communication between port 11^a and exhaust-port 33 and permits air to flow directly from port 47 to port 11^a. Then as the pressure in the pipe which is being supplied by port 11^a rises the pressure on the outer side of piston 30 opposes the pressure on the inner side of piston 29, and by reason of the relative dimensions of these pistons the valve 27 will be moved to close the port 11^a when the pressure in the pipe has reached twenty-five pounds. In the next position of the valve, (indicated by 26^b in Fig. 6) the passage 44, which leads to the space between the pistons 29 and 30, is disconnected from atmosphere and is supplied with air at forty pounds pressure through a small port 50 in the main valve. The pipe connected to port 11^a will now be supplied with air at forty pounds pressure, since the pressure on the inner side of the piston 30 is forty pounds, and it will therefore require forty pounds on the other side of this piston before the valve 27 is closed. In the third position of the main valve, as at 26^c in Fig. 7, passage 44 is again connected to atmosphere through port 51 in the main valve and port 39. Consequently the total pressure of the inner side of the connected pistons 29 and 30 is less than that on the outer side, and the valve 27 will be moved to its normal position, permitting air to flow from port 11^a, through port 33, to atmosphere until pressure at twenty-five pounds has been reached, whereupon the pressure against piston 29 will cause the valve 27 to be moved toward the left and again close communication between port 11^a and atmosphere. At the same time port 48, leading to the inner side of the piston 31, is opened by reason of the end of the valve 27 passing beyond said port. Air at forty pounds pressure will now be admitted to the inner side of piston 31, forcing it and the valve 28 outwardly. It will be noted that the port 41 has moved from the ports 39^b and 40, so that chamber 36 is shut off from atmosphere, but still in communication with port 12^a. Air will therefore be supplied to the pipe connected to port 12^a until a pressure is reached which will cause the piston 32 to move the valve 28 to the left against the opposed pressure on piston 31 and close said port, the relative proportions of the pistons 31 and 32 being such that the supply of air to port 12^a will be shut off when a pressure of seven and a half pounds has been reached. In the final position of the valve (indicated at 26^d in Fig. 7) passage 44 is again supplied with air at forty pounds pressure through the port 52 in the main valve, and consequently the pipe connected to port 11^a will be again supplied with air at forty pounds pressure. In Fig. 1 the pipe 1 is shown as connected to port 12 and pipe 2 to port 11. In Fig. 4 the plug-valve *v* is shown

in its other operative position, connecting pipe 1 to pipe 12^a and pipe 2 to pipe 11^a.

Although I have described in detail a preferred form of apparatus embodying the present invention, together with a suitable valve mechanism and motor-controller well adapted for operation in connection therewith, I do not desire to limit the present invention to the particular apparatus shown, nor to its use in connection with any one form of control apparatus or master-valve mechanism.

What I claim as new, and desire to secure by Letters Patent of the United States, is—

1. In a system of control, a reversing-switch, electromagnetic actuating means therefor, a relay arranged to complete a circuit through said actuating means for causing the reversing-switch to be moved into one operative position, a second relay arranged to complete a circuit through said actuating means for causing the reversing-switch to be moved into its other operative position, means whereby the operation of one relay interrupts the controlled circuit of the other relay, and means for controlling said relays.

2. In a system of control, a reversing-switch, actuating means therefor, a pair of relays for controlling the operation of said actuating means, and means whereby each relay in its operative position renders the other relay inoperative to control the said actuating means.

3. In a system of control, a reversing-switch, an electromagnet for moving it into one operative position, a second electromagnet for moving it into its other operative position, a relay for controlling the actuating-circuit of each of said electromagnets, pneumatic actuating means for said relays, and a contact in each actuating-circuit arranged to be opened when the controlling-relay of the other circuit is operated.

4. In a system of control, a motor-controller, pneumatic controlling means therefor, two pipes connected to said controlling means, and a master-valve arranged to admit to said pipes air varying in degree of compression, the arrangement being such that the direction of rotation of the motor or motors depends upon the order in which the pipes are energized and said master-valve being constructed and arranged to admit to the second pipe-air at a lower degree of compression than the lowest which is admitted to the first pipe.

5. In a system of control, a motor-controller including a reversing-switch, pneumatic relays including two reversing-relays for controlling said controller, two pipes connected to said relays, one pipe being connected to each reversing-relay, the arrangement being such that both pipes must be energized in order to give a complete cycle of control connections, and a master-valve for admitting

air to said pipes at varying degrees of pressure, said valve being so arranged that the air which is admitted to the second pipe to be energized is of a pressure insufficient to operate the reversing-relay.

6. In a system of control, a motor-controller including a reversing-switch, a series of pairs of relays including a pair of reversing-relays for controlling the operation of said controller, pneumatic actuating means for said relays arranged to close said pairs of relays at different pressures, two pipes connecting corresponding relays of each pair, a master-valve for admitting to said pipes fluid varying in degree of compression, the arrangement being such that both pipes must be energized to give a complete cycle of connections and the master-valve being arranged to supply either of said pipes only with air at a pressure insufficient to operate the reversing-relay.

7. In a system of control, a series-parallel motor-controller, including a reversing-switch, pneumatic relays including a pair of parallel relays both of which must be closed in order to give the parallel motor connections and two reversing-relays for controlling the operation of said motor-controller, two pipes each connected to a reversing-relay and to a parallel relay, and a master-valve arranged to admit to said relays air varying in degree of compression.

8. In a system of control, a series-parallel motor-controller including a reversing-switch, relays including a pair of reversing-relays and a pair of parallel relays for controlling the operation of said motor-controller, the arrangement being such that both parallel relays must be operated to produce the parallel connections, pneumatic actuating means for said relays including actuating means for the parallel relays arranged to operate at a lower pressure than the pressure at which the reversing-relays operate, a pair of pipes connected to said actuating means, and means for supplying compressed fluid to either of said pipes at pressures sufficient to operate all of the relays connected thereto and to the other pipe at a pressure sufficient only to operate the parallel relay.

9. In a system of control, a motor-controller, a series of pairs of relays for governing said controller, pneumatic actuating means for said relays arranged to operate at different pressures, two pipes connecting corresponding relay-actuating means of said pairs, and means for supplying to said pipes air varying in degree of compression, the arrangement being such that both relays of one pair and either relay of each of the other pairs provides for a complete cycle of controller connections, the direction of rotation of the motor depending upon the order in which said pipes are energized.

10. In a system of control, a motor-con-

troller comprising a reversing-switch, individual series and parallel switches and a plurality of resistance-switches, a series of pairs of controlling-relays including pairs of reversing, resistance and parallel relays, pneumatic actuating means for said relays, two pipes connecting corresponding relays of said pairs, and a master-valve for admitting compressed air to each pipe during each cycle of operation for forward or reverse rotation of the motor or motors.

11. In a system of control, a motor-controller comprising individual series, parallel and resistance switches and a reversing-switch, controlling-relays including a pair of reversing-relays and a pair of parallel relays, pneumatic actuating means for said relays so arranged that the parallel relays are operated at less pressure than the reversing-relays, two pipes connected to the actuating means of said relays, each pipe being connected to the actuating means of a reversing-relay and of a parallel relay, and means for supplying either pipe with compressed fluid having sufficient pressure to operate all of the relays associated therewith and the other pipe with fluid having only sufficient pressure to operate the parallel relay, whereby a complete cycle of connections for forward or reverse rotation of the motor or motors may be obtained.

12. In a system of control, a motor-controller comprising a reversing-switch, indi-

vidual series and parallel switches and a plurality of resistance-switches arranged to operate in automatic succession, a series of pairs of controlling-relays including pairs of reversing, resistance and parallel relays, pneumatic actuating means for said relays so arranged that the parallel relays operate at a lower pressure than that at which the reversing-relays operate, two pipes connecting corresponding relays of said pairs, and means for supplying either of said pipes with fluid at proper pressures for operating all of said relays and the other pipe with fluid having a pressure sufficient only to operate the parallel relay, whereby a complete cycle of connections for forward or reverse rotation of the motor or motors may be obtained.

13. In a system of control, a motor-controller comprising a reversing-switch, individual series and parallel switches and a plurality of individual resistance-switches arranged to be operated in automatic succession, a plurality of individual separately-actuated relays for controlling the reversing, parallel and resistance switches respectively, and means for controlling said relays.

In witness whereof I have hereunto set my hand this 19th day of May, 1905.

GEORGE H. HILL.
